PUSHBUTTON OPERATED OVERLOAD SWITCH
Jakob Ellenberger, Altdorf, near Nurnberg, Germany, assignor to Ellenberger & Poensgen G.m.b.H., Altdorf, near Nurnberg, Germany, a firm of Germany

Filed Oct. 20, 1960, Ser. No. 63,761

Claims priority, application Germany Oct. 26, 1959
11 Claims. (Cl. 200—116)

The present invention relates to improvements in a pushbutton-operated overload switch which is provided with an automatic release mechanism which may be thermally and/or electromagnetically controlled, as well as with a manual release device.

In most overload switches of this kind which are presently known a pushbutton is provided for manually releasing the switch. This pushbutton is usually smaller than the main pushbutton for connecting the switch and it is located closely adjacent to the latter. The actuation of the individual pushbuttons is therefore rather difficult, especially if the respective overload switch is of a very narrow construction. It may then occur very easily that when one pushbutton is being depressed, the other may accidentally also be depressed. The desired movement of the control member of the switch which is effected by depressing one pushbutton will then be counteracted by the unintentional movement of the other pushbutton.

It is an object of the present invention to provide an overload switch, and especially one of a very narrow construction, in which each of the two pushbuttons for connecting the switch and for manually releasing it may be separately operated without danger that the other pushbutton may also be operated and in which the manual release button may also be more easily operated than the small pushbutton of the known overload switches which is movable parallel to the connecting button thereof.

This object may be attained according to the invention by providing the manual release button in the form of a two-armed lever which is pivotably mounted within the switch housing and the outwardly projecting end of which, the actual release button, may be operated by pushing it in the direction toward the axis of the main connecting button. Since the connecting button may be operated by a pressure in a direction vertical to the base on which the switch is mounted, while the lever for manually releasing the switch is operated by a pressure in a direction substantially at a right angle to the direction of movement of the connecting button, it will be practically impossible to operate the release lever while the connecting button is being depressed, or vice versa to pivot the release lever and at the same time to depress the connecting button.

In order to improve the grip on the outwardly projecting or button end of the manual release lever, this end of the lever is provided with an inclined surface which ascends in steps in the direction toward the connecting button. According to a further feature of the invention, the lever is pivotably mounted on a hollow rivet which also serves the purpose of connecting the two parts of the switch housing to each other and to receive a bolt for securing the switch in a fixed position. This hollow rivet obviates the necessity of providing the switch with special bores or flanges for mounting the same and it also permits the arrangement of several similar overload switches adjacent to each other and to connect them to each other by a bolt which is passed through the hollow rivets in all of these switches. If desired, this same connecting bolt may then also be used to mount the entire row of overload switches. In order to improve this connection the side of the switch housing opposite to that

2

in which the hollow rivet is secured may also be provided with a recess into which a further mounting or connecting bolt may be inserted. Such a row of overload switches may, for example, be applied in a motor vehicle in place of the conventional replaceable fuses which are inserted in fuse clamps on a common base. For this purpose, the invention further provides that the terminal strips of each overload switch may be made in the form of plug pins or plug strips so that the overload switches may be plugged into the spring contacts on a common base which may be, for example, of the same kind as used in a motor vehicle for replaceable fuses. Although these plug pins or plug strips may also project from the switch housing a very compact space saving switch construction may be attained according to the invention by providing the terminal strips which are made in the form of plug pins or plug strips entirely within the length of the switch.

According to another feature of the invention which is applicable particularly if several overload switches are to be connected to each other, the connecting bolts may also be used for securing angle brackets to the ends thereof. In this case, it will not be necessary to secure the individual switches to a terminal or fuse base since the entire row of switches may then be mounted in a fixed position by means of these brackets. The terminal or fuse base may then be omitted.

Instead of providing the overload switch according to the invention with terminal strips, the switch may according to a further feature of the invention be provided with plug pins which are slotted and may have a thicker bulge on their ends. These plug pins may be held by a clamping action in metal sockets in a base plate, and after being inserted into the sockets from one end thereof, the thicker ends of the plug pins will engage with the edges of the sockets at the other side thereof.

These objects, features, and advantages of the present invention will become further apparent from the following detailed description, particularly when read with reference to the accompanying drawings, in which—

FIGURE 1 shows a side view of an overload switch according to the invention;

FIGURE 2 shows a view of the switch as seen from the right of FIGURE 1;

FIGURE 3 shows a view of the switch as seen from the left of FIGURE 1;

FIGURE 4 shows a top view of the switch according to FIGURE 1;

FIGURE 5 shows an enlarged side view of the switch according to FIGURE 1 in the opened position and inserted into a fuse base;

FIGURE 6 shows a view of two overload switches according to FIGURE 5 and as seen from the right thereof when inserted into a fuse base;

FIGURE 7 shows a side view of a modification of the overload switch according to the invention;

FIGURE 8 shows a view of the switch according to FIGURE 7, as seen from the left thereof; while

FIGURE 9 shows a top view of the switch according to FIGURE 7.

Referring first to FIGURES 1 to 5 of the drawings, the overload switch according to the invention which may be internally designed, for example, in a manner similar to the overload switch as described and illustrated in my previous United States Patent No. 2,895,028, is provided with a housing of insulating material which consists of two parts, in which part 1 contains the various switch elements, while part 2 serves as a cover which secures the inserted elements in a fixed position in part 1. For electrically connecting the overload switch, the same is provided with terminal strips 3 and 4 which have conical projections 5 and 6 at their ends. When the switch is

inserted, for example, into a fuse base 7 as used in a motor vehicle, projection 5 will resiliently engage into a bore 8 in a contact spring 9 which is secured to a connecting terminal 12 on base 7, while projection 6 will engage into a corresponding conical recess 10 in a connecting terminal 11. Terminal strip 3 has a contact 13 thereon which is operatively associated with a contact 14 on an angular contact bridge 15. When contact bridge 15 is in the disconnecting position, as shown in FIGURE 5, its arm 16 engages with an obliquely inclined surface 17 on the housing part 1 and is held in this position by a pair of projections 18 which are provided on both sides of a control rod 19 on pushbutton 20 and are slidably guided in suitable recesses in the two housing parts 1 and 2. The upper ends of projections 18 engage with a pair of lateral arms 21 on contact bridge 15 and thus pivotably support the latter. Arm 16 on contact bridge 15 is further provided with a large bore into which control rod 19 is inserted and which permits the contact bridge to slide loosely in the axial direction along control rod 19. The lower end of control rod 19 carries a member 22 which is secured thereto and is operatively associated with a projection 23 on contact bridge 15. Control rod 19 carries two compression springs 24 and 25, the first of which acts at one side upon pushbutton 20 and at the other side upon a washer 27 which is inserted into a recess 26 in the housing. The other compression spring 25 which acts at one side upon arm 16 of contact bridge 15 and at the other side upon member 22 effects the trip-free release of the switch.

For arresting contact bridge 15 in the connecting position, the switch is provided with a bimetallic strip 28 which has a detent 29 on its free end portion which, when contact bridge 15 is in the connecting position, engages behind contact 30 on arm 16 of the contact bridge. Bimetallic strip 28 carries a heating coil 31 which is electrically connected at one end 32 to the bimetallic strip and at the other end to terminal strip 4.

By means of a two-armed lever 33 which consists of insulating material the bimetallic strip 28 may be manually pivoted to its inoperative position in which detent 29 is disengaged from contact 30 on contact bridge 15. Lever 33 is pivotably mounted on the housing on a hollow rivet 34 which also connects the two housing parts 1 and 2 to each other. The two parts of the housing are further connected to each other by a second hollow rivet 35. The outer end 33' of lever 33 which projects from housing 1, 2 is provided with a step-shaped inclined surface 37 which permits the lever to be more easily manipulated. The lower arm 36 of lever 33 is adapted to engage with a notched-out tab 28' on the bimetallic strip 28. While pushbutton 20 may be depressed in a vertical direction, as seen in FIGURE 5, lever 33 may be pivoted for manually releasing the switch by being pushed at its end 33' in the direction toward the axis of the pushbutton.

The operation of the overload switch as illustrated in FIGURES 1 to 5 is as follows:

Referring particularly to FIGURE 5 which shows the switch in the disconnected position, pushbutton 20 must be depressed in order to engage the switch and to move contact bridge 15 to the connecting position. Member 22 on control rod 19 will then engage with the projection 23 and take contact bridge 15 along until the detent 29 on bimetallic strip 28 will snap over contact 30 on contact bridge 15. By the same movement, contact 14 will also be applied against contact 13 on terminal strip 3 so that the circuit within the overload switch will be closed.

If an excess current occurs, bimetallic strip 28 will be heated by heating coil 31 and thereby be bent toward the right, as seen in FIGURE 5, so that detent 29 on strip 28 will disengage from contact bridge 15 which will then be moved back to the disconnecting position, as

shown in FIGURE 5, by the projections 18 and the action of compression spring 24.

The bimetallic strip 28 may also be bent manually by an operation of lever 33. For this purpose, a pressure 5 is exerted upon the outer end 33' of lever 33 in the direction toward pushbutton 20 so that lever 33 will be pivoted about rivet 34 in the counterclockwise direction and the lower arm 36 of the lever will press upon the outwardly bent tab 28' of the bimetallic strip and thereby bend the latter toward the right so that detent 29 will disengage from and release contact bridge 15. After lever 33 has been released, it returns under the spring action of the bimetallic strip 28 to its original position, as shown in FIGURE 5.

FIGURE 6 illustrates the manner in which several switches may be connected to each other to secure them in a fixed position. The adjacent switches may then be separated by a spacing sleeve 40 and a connecting bolt 38 may be passed through the hollow rivets 34 and spacing sleeve 40, and nuts 39 may then be screwed tightly upon the threaded ends of the bolt. At the side of the housing opposite to that carrying the hollow rivet 34, a recess 41 is provided into which another bolt 38 may be inserted for further securing the individual switches 25 to each other.

As shown in FIGURE 6, a row of two or more connected switches may be inserted into a fuse or terminal base 7, although such a base may also be omitted, in which event the row of switches may be mounted in a 30 fixed position by means of angle brackets 42 serving as mounting flanges, as indicated in FIGURE 6 in dotted lines, which may be secured to the two outer switches by means of the connecting bolts 38.

In the modification of the overload switch, as illustrated in FIGURES 7 to 9, the two terminal strips 43 and 44 which are likewise made in the form of plug pins project from the switch housing 1, 2. This switch is likewise provided with a two-armed lever 33 which is pivotably mounted on a hollow rivet 34 and the outer end 40 33' of which also projects from the housing and may be easily manipulated in the same manner as described with reference to the switch according to FIGURES 1 to 6.

If a special terminal or fuse base is to be omitted the 45 terminal strips 3 and 4 may also be modified in any suitable manner in order to permit the simplest possible connection to the power lines. Thus, for example, the power lines may be soldered to the terminal strips or these strips may be designed and spaced from each other so as to permit the overload switch to be plugged into a standard wall plug.

Instead of providing the overload switch according to the invention with terminal strips, it is—of course—also possible to provide it with plug pins by designing the 55 switch in a manner similarly as described and illustrated in my previous United States Patent No. 2,767,281, in which case it will not be necessary to connect several adjacent switches to each other by bolts or screws since the plug pins will then insure a proper and secure mounting of the switches.

Although my invention has been illustrated and described with reference to the preferred embodiments thereof, I wish to have it understood that it is in no way limited to the details of such embodiments, but is capable 65 of numerous modifications within the scope of the appended claims.

Having thus fully disclosed my invention, what I claim is:

1. In an overload switch, in combination, a movable 70 connect-and-disconnect member operable to a connect position and to a disconnect position for making and breaking an electrical connection, a first pushbutton cooperative with said member having an axis and operable in a direction corresponding with said axis for actuating said member to said connect position, means automati-

ically engageable with said member for releasably locking said member in said connect position, means constantly urging said member toward said disconnect position, means cooperative with said locking means operable automatically for releasing said member from a locked condition when an overload occurs, and means operable at will comprising a second pushbutton cooperative with said means for releasably locking said member and operable in a direction normal to said axis for causing said locking means to release said member.

2. In an overload switch having a housing, in combination, in said housing a movable connect-and-disconnect member in said housing operable to a connect position and to a disconnect position for making and breaking an electrical connection, a first pushbutton extending outwardly of said housing cooperative with said member having an axis and operable in a direction corresponding with said axis for actuating said member to said connect position, means automatically engageable with said member for releasably locking said member in said connect position, means constantly urging said member toward said disconnect position, means cooperative with said locking means operable automatically for releasing said member from a locked condition when an overload occurs, and means operable at will comprising a second pushbutton extending outwardly of said housing cooperative with said means for releasably locking said member and operable in a direction normal to said axis for causing said locking means to release said member.

3. In an overload switch, having a housing, in combination in said housing connecting means comprising a movable connect-and-disconnect member in said housing operable to a connect position and to a disconnect position for making and breaking an electrical connection, a first pushbutton extending outwardly of said housing cooperative with said member having an axis and operable in a direction corresponding with said axis for actuating said member to said connect position, means automatically engageable with said member for releasably locking said member in said connect position, means constantly urging said member toward said disconnect position, means cooperative with said locking means operable automatically for releasing said member from a locked condition when an overload occurs, means operable at will comprising a second pushbutton extending outwardly of said housing cooperative with said means for releasably locking said member and operable in a direction normal to said axis for causing said locking means to release said member, and said connecting means comprising terminal strips forming plug pins for connecting said switch in circuit.

4. In an overload switch according to claim 3, in which said plug pins are mounted within the overall length of said housing.

5. In an overload switch according to claim 3, in which said plug pins extend outwardly of said housing.

6. In an overload arrangement comprising a plurality of overload switches mounted side-by-side, each overload switch having a housing, in each housing a movable connect-and-disconnect member in said housing operable to a connect position and to a disconnect position for making and breaking an electrical connection, in each switch a first pushbutton extending outwardly of said housing cooperative with said member having an axis and operable in a direction corresponding with said axis for actuating said member to said connect position, in each switch means automatically engageable with said member for releasably locking said member in said connect position, in each switch means constantly urging said member toward said disconnect position, in each switch means cooperative with said locking means operable automatically for releasing said member from a locked condition when an overload occurs, in each switch means operable at will comprising a second pushbutton extend-

ing outwardly of said housing cooperative with said means for releasably locking said member and operable in a direction normal to said axis for causing said locking means to release said member, and means extending between the housings of said plurality of housings for holding said switches in a fixed arrangement in a side-by-side disposition.

7. In an overload switch having a housing, in combination, in said housing connecting means comprising a movable connect-and-disconnect member in said housing operable to a connect position and to a disconnect position for making and breaking an electrical connection, a first pushbutton extending outwardly of said housing cooperative with said member having an axis and operable in a direction corresponding with said axis for actuating said member to said connect position, means automatically engageable with said member for releasably locking said member in said connect position, means constantly urging said member toward said disconnect position, means cooperative with said locking means operable automatically for releasing said member when an overload occurs, means operable at will comprising a second pushbutton extending outwardly of said housing cooperative with said means for releasably locking said member and operable in a direction normal to said axis for causing said locking means to release said member, said connecting means further comprising a two-arm lever cooperative with said second pushbutton and said locking means and operatively connecting them, said housing comprising two parts, at least one hollow rivet connecting said two parts to each other, said lever being pivotally mounted on said rivet, and said rivet having a bore adapted to receive at least one bolt for mounting said switch in a fixed position.

8. In an overload switch according to claim 7, in which said housing has a slot-shaped opening on a side thereof to receive a mounting bolt.

9. In an overload switch having a housing, in combination, in said housing connecting means comprising a movable connect-and-disconnect member in said housing operable to a connect position and to a disconnect position for making and breaking an electrical connection, a first pushbutton extending outwardly of said housing cooperative with said member having an axis and operable in a direction corresponding with said axis for actuating said member to said connect position, means automatically engageable with said member for releasably locking said member in said connect position, means constantly urging said member toward said disconnect position, means cooperative with said locking means operable automatically for releasing said member from a locked condition when an overload occurs, means operable at will comprising a second pushbutton extending outwardly of said housing cooperative with said means for releasably locking said member and operable in a direction normal to said axis for causing said locking means to release said member, said connecting means comprising plug pins and a base plate having metal sockets for releasably receiving said plug pins, an enlargement on each of said pins, and said sockets for receiving said pins having recesses for releasably receiving said enlargements.

10. In an overload switch, having a housing, in combination, in said housing connecting means comprising a movable connect-and-disconnect member in said housing operable to a connect position and to a disconnect position for making and breaking an electrical connection, a first pushbutton extending outwardly of said housing cooperative with said member having an axis and operable in a direction corresponding with said axis for actuating said member to said connect position, means automatically engageable with said member for releasably locking said member in said connect position, means constantly urging said member toward said disconnect position, means cooperative with said locking means operable automatically for releasing said member from a

locked condition when an overload occurs, means operable at will comprising a second pushbutton extending outwardly of said housing cooperative with said means for releasably locking said member and operable in a direction normal to said axis for causing said locking means to release said member, and said second pushbutton comprising a stepped surface manually engageable for actuating said second pushbutton, disposed outwardly of said housing comprising steps ascending in a direction toward said first pushbutton.

11. In an overload arrangement comprising a plurality of overload switches mounted side-by-side, each overload switch having a housing, in each housing a movable connect-and-disconnect member in said housing operable to a connect position and to a disconnect position for making and breaking an electrical connection, in each switch a first pushbutton extending outwardly of said housing cooperative with said member having an axis and operable in a direction corresponding with said axis for actuating said member to said connect position, in each switch means automatically engageable with said member for releasably locking said member in said connect position, in each switch means constantly urging said member toward said disconnect position, in each switch means

15

5
